UNITED STATES PATENT OFFICE.

JONATHAN HARRIS, OF CLEVELAND, OHIO.

DESIGN FOR A FENCE-FASTENER.

SPECIFICATION forming part of Design No. 25,614, dated June 9, 1896.

Application filed March 27, 1896. Serial No. 585,133. Term of patent 14 years.

To all whom it may concern:

Be it known that I, JONATHAN HARRIS, a citizen of the United States, and a resident of Cleveland, in the county of Cuyahoga, State 5 of Ohio, have invented and produced a new and original Design for Fence-Fasteners, of which the following is a specification, reference being had to the accompanying drawings, showing a part thereof.

10 In the drawings, Figure 1 is a side elevation. Fig. 2 is an end view, and Fig. 3 is a central longitudinal section exhibiting my design in full.

In the figures, 1 is a cylindrical figure provided with plain terminal faces 2, cutting the cylinder at right angles. In addition to this leading feature circular openings are 15 shown in the periphery, arranged at 3 dia-

metrically opposite, in the position in which they would be projected on the periphery by two smaller transverse cylinders intersecting therewith at right angles to one another and closely adjacent, as shown in full and dotted lines.

The general appearance of this design is 25 that of a cylinder with plain terminal faces and circular openings, as described.

I claim, therefore—

The design for a fence - fastener, herein shown and described.

JONATHAN ^{his} ~~X~~ HARRIS.
